Attorney

UNITED STATES PATENT OFFICE

PAUL V. HOECHER, OF CHICAGO, ILLINOIS, ASSIGNOR OF ONE-HALF TO JAMES C. OLIVER, OF CHICAGO, ILLINOIS

ELECTRIC SOCKET CONSTRUCTION

Application filed April 15, 1929. Serial No. 355,391.

The present invention relates to improvements in electric sockets and has for its principal object to provide a socket unit in the form of a strip of molding that is adapted to be secured on a wall, said unit being of such construction as to permit one or more electric plug cap units to be detachably mounted thereon for supplying current to the member or members with which the cap units are associated.

One of the important objects of the present invention is to provide an electric socket construction which will afford a quick detachable connection for the male unit of the electric connection, and this in a positive and efficient manner.

A still further object is to provide a structure of the above-mentioned character that may be incorporated in an ornamental molding strip that is secured to a wall or the like.

Another object is to provide an electric socket construction of the above-mentioned character that includes the provision of a pair of spaced bus-bars arranged within an insulating base, each bus-bar including an elongated strip of metal that is bent back upon itself to form coacting spring jaws between which the respective prongs or contacts of the male unit or cap are adapted to be disposed when an electrical connection is desired.

Another important object is to provide an electric socket construction of the above-mentioned character which is simple, inexpensive, strong and durable and further well adapted for the purposes for which it is designed.

Other objects and advantages of the invention will become apparent from the following description when taken in connection with the accompanying drawings.

In the accompanying drawings wherein like reference characters indicate corresponding parts throughout the same;

Figure 1 is a view partly in elevation and partly in section of the adjacent walls of a room showing my improved electrical socket construction secured on the respective walls, one of the socket structures being shown in elevation, and the other in section and also il-

lustrating the manner in which the cap unit is attached to one of the sockets.

Figure 2 is a vertical sectional view taken approximately on the line 2—2 of Figure 1;

55

Figure 3 is a similar section taken substantially on the line 3—3 of Figure 1.

In the drawings wherein for the purpose of illustration is shown the preferred embodiment of my invention, the numeral 1 designates generally the molding strip with which my improved electric socket is associated. This molding includes an insulating base 2 having a metallic covering 3 therefor and upon referring to Figures 1 and 2 of the drawings, it will be observed that the front face of the insulating base 2 is uncovered. Any appropriate fastening means such as is indicated at 4 extends through suitable openings formed centrally in the insulating base 2 and through the rear side of the ornamental covering 3 for securing the molding strip to the wall A or other support. If desired, the edge portion of the insulating base may be shaped to provide any desirable ornamental design and obviously the metallic covering 3 will be bent to conform to the shape of the insulating base.

Upper and lower longitudinally extending slots 5 and 6 respectively are formed in the front face of the insulating base 2, the inner ends of the slots terminating adjacent the rear wall of the insulating base and these slots extend for the full length of the insulating base. Upon referring to Figure 1 it will be observed that the ornamental covering 3 extends beyond one end of the insulating base in order to accommodate the fitting 7 that extends through an opening formed in the rear wall of the projecting end portion of the covering 3 in order to accommodate the lead in wires 8 that supply the current to the bus-bars arranged within the respective grooves or slots 6 and the usual tubular covering for these lead in wires is shown at 9 in Figure 3.

The insulating base 2 is further formed with the longitudinally extended rectangular shaped slots or channels 10 and 11 respectively that intersect the upper and lower slots

95

100

5 and 6 respectively in the manner as clearly indicated in Figures 1 and 2 and these vertically disposed slots also extend for the full length of the insulating base.

8 Arranged within the inner end portions of the upper and lower longitudinally extending horizontally disposed slots 5 and 6 are the bus-bars 12 and 13 respectively. Each of these bus-bars is of substantially U-shaped 10 formation in end elevation, and the free ends of the arms are so bent as to provide normally contacting jaws 14 and 15 with the free ends of the jaws disposed outwardly in opposite directions for disposition within the respective vertical slots.

15 These metallic bus-bars are insertible within the respective horizontally disposed slots formed in the insulating base 2 from the ends of said insulating base and are frictionally held in position. The free ends of 20 the lead in wires 8 are soldered to the end portions of the respective bus-bars as suggested in Figure 1.

25 The slots 5 and 6 are spaced a suitable distance apart to accommodate the usual projecting contacts 16 and 17 carried by the insulating cap 18 that forms the other part of the electrical connection and the conductor wires 19 that are associated with the embedded ends of the contacts 16 and 17 are 30 adapted to be connected with any suitable member to which current is supplied when the cap unit is engaged with the socket carried by the molding strip and such member 35 may be a lamp, curling iron, cooking utensil, electric refrigerator and the like.

40 The contacts 16 and 17 are insertible in a quick detachable manner in the slots 5 and 6 respectively so that the free ends of the contacts will forcibly enter between the coacting jaws 14 and 15 of the respective bus-bars and when the contacts are inserted between the coacting jaws, the free ends thereof will move outwardly in the respective vertical 45 channels or slots 10 and 11 in the manner as suggested more clearly in Figure 2. These jaws will cooperate with the contacts to maintain the cap unit in engagement with the socket and the inner face of the cap will 50 abut against the covered front face of the insulating base of the molding strip.

55 The provision of an electric socket of this character will permit one or more cap units to be detachably engaged therewith and by forming the socket in the manner as shown and described, electric connection may be obtained without the loss of much time or labor and furthermore the opposed jaws of each bus-bar will prevent the accidental 60 disengagement of the cap unit from the socket.

65 A structure of this character may be incorporated in an ornamental molding strip and will not detract from the appearance of the room where the molding strip is secured to the wall or support. Further, an

electric socket of this construction may be assembled at a very low cost and the parts are so arranged as to permit the same to be readily accessible whenever necessary.

70 While I have shown the preferred embodiment of my invention, it is to be understood that minor changes in the size, shape and arrangement of parts may be resorted to without departing from the spirit of the invention or the scope of the appended claims. 75

What is claimed is:

1. In a structure of the class described, an insulating base formed with spaced elongated slots, bus-bars arranged within the respective slots to provide an electric socket for receiving the contacts of a conventional cap, and lead in wires connected to the respective bus-bars, said bus-bars comprising a substantially U-shaped metallic member having the crown portion thereof disposed against the inner end of the respective slots, the free end portions of the arms of said U-shaped member being disposed normally in contacting relation to form opposed jaws between which the respective contacts of the cap unit is forcibly disposed, the free ends of the jaws being directed outwardly in opposite directions, the insulating base being formed with additional slots that intersect the aforementioned slots to accommodate the projecting ends of the arms of the respective U-shaped member.

2. In combination, a molding strip including an insulating base adapted to be secured to a support, said insulating base being formed with longitudinally extending spaced slots that extend inwardly from the front face thereof, substantially U-shaped bus-bars arranged within the respective slots, lead in wires connected to the respective U-shaped bus-bars, the free end portions of the arms of each U-shaped bus-bars being disposed in normally contacting relation to provide opposed jaws as and for the purpose described, the free ends of the arms being directed outwardly in opposite directions, the insulating base being formed with slots that intersect the aforementioned slots to accommodate the outwardly projecting ends of the arms of the respective U-shaped bus-bars.

115 In testimony whereof I affix my signature.
PAUL V. HOECHER.
